UNITED STATES PATENT OFFICE.

JOHN C. OLIVA, OF MARENKO, IOWA.

SHOE-SCRAPING DEVICE.

988,207.

Specification of Letters Patent. Patented Mar. 28, 1911.

Application filed February 28, 1910. Serial No. 546,450.

To all whom it may concern:

Be it known that I, JOHN C. OLIVA, a citizen of the United States, residing at Marengo, in the county of Iowa and State 5 of Iowa, have invented a certain new and useful Shoe-Scraping Device, of which the following is a specification.

The object of my invention is to provide a shoe scraping device of simple, durable and 10 inexpensive construction that may be formed complete of a single piece of material and that may readily and easily be driven into the ground and that is provided with means for limiting the downward movement of the 15 scraper into the ground and that is also strongly and firmly braced and reinforced.

A further object is to provide a device of this kind that may be formed complete of a single piece of sheet metal in such a manner 20 that the metal will have a double thickness throughout the entire device and also in such a manner that it is strengthened and reinforced at the various points where the greatest strain or weight occurs.

25 My invention consists in certain details in the construction of the shoe scraper whereby the objects contemplated are attained, as hereinafter more fully set forth, pointed out in my claims and illustrated in 30 the accompanying drawings, in which:

Figure 1 shows a front elevation of a device embodying my invention made of cast metal. Fig. 2 shows a side elevation of same. Fig. 3 shows a view similar to Fig. 1 35 illustrating a device embodying my invention made of a single piece of sheet metal. Fig. 4 shows a side elevation of same, and Fig. 5 shows a plan view of a blank piece of sheet metal cut out as required to form my 40 improved shoe scraper. The dotted lines in said figure show the lines along which the sheet metal is folded.

45 Referring to the accompanying drawings, the head of the device is indicated by the numeral 10. Its top central portion is preferably flat at 11 to form a scraper for the sole of a shoe. At the sides of the part 11 are the upwardly extended lugs 12 which 50 preferably extend inwardly at their upper ends toward the center of the part 11 for the purpose of scraping a shoe above the sole. At the bottom of the head 10 is a flange 13 arranged in a substantially horizontal position and below the flange 13 is the body 55 portion 14 which is preferably tapered to a point at its lower end. On one side of the

body portion 14 is a reinforcing rib 15 also tapered to a point at its lower end, the upper end of said rib being formed integral with the flange 13.

60

In the form of the invention shown in Figs. 1 and 2, there is also a rib 16 extending through the flange 13 to the central portion of the part 10 to strengthen and reinforce the rib and the part 10.

65

In the form of my invention which is made complete of a single piece of sheet metal the blank for forming the shoe scraper is cut out in the manner shown in Fig. 5. In this form of my invention the part above 70 ground comprises a body portion 17 provided with an opening 18 so arranged that when folded along the dotted lines 19, there will be a double thickness of the parts corresponding to the part 10 as shown in Fig. 75

1. Furthermore at one end of the part 17 is an extension 20 having a slot 21 and two side flaps 22, and in the opening 17 is a side reinforcing flap 23 for purposes hereinafter made clear. The part of the device to be 80

inserted below the ground comprises a body portion 24 tapered to a point at its lower end. In folding the part 24, I first bend the sides thereof along the lines 25 to form a double thickness of material and I then bend 85

it along the lines 26 so that the remaining parts outside of said lines 26 constitute ribs or flanges 27. At the upper ends of the ribs or flanges 27 are the lugs 28 which are so arranged as to fold along the lines 29 upwardly and toward the body portion of the device above ground and said parts 28 constitute the flanges for limiting the downward movement of the device into the 90 ground. After the parts that go below the ground have been folded then the head of the device is doubled along the line 19 and the slot 20 will receive the upper end of the reinforcing ribs 27 to hold them together and 95

then the flanges 22 are folded over back of the scraper to firmly hold the parts together. Then the part 23 is folded over the flat surface which constitutes the portion of the foot 100 scraper that receives the sole of the shoe to thereby strengthen and reinforce the device at this point where the greatest wear takes place.

It also prevents the two parts of the head from spreading away from each other so that on account of the peculiar construction and arrangement of the sheet metal portions, the entire device may be made of a single piece of sheet metal and there is not 105 110

only a double thickness throughout the entire device but in addition to this the parts are all strengthened and reinforced where it is necessary to hold them together to 5 make a firm, strong and durable device out of a single piece of comparatively thin sheet metal.

In the form of the invention shown in Fig. 3, I have provided at the top of the 10 scraper the outward projecting lugs 30 which may be used in scraping mud from a shoe and I have also rounded the body portion of the scraper at 31 for convenience in scraping shoes.

15 It is obvious that with either form of my improved scraper the device may be readily and easily driven into the ground and its downward movement into the ground would be limited by the flange. It will be firmly 20 and securely held in its position in the ground on account of the shape of the part below ground and the part above ground is especially adapted for use in cleaning shoes in a thorough and complete manner.

25 I claim as my invention:

1. An improved shoe scraper, comprising a head having a substantially flat top and lugs projecting upwardly at the sides and the top to engage a shoe above the sole, a body 30 portion tapered at its lower end and designed to be inserted in the ground, a reinforcing rib on said body portion and a flange between the head and the body portion formed integral with said reinforcing rib, said

flange being designed to limit the downward 35 movement of the device in the ground.

2. In a device of the class described, a single piece of sheet metal comprising a body portion tapered to a point at its lower 40 end and having its sides doubled over adjacent to each other at the longitudinal center 45 of the device and having its side edge portion projected away from the body portion and parallel with each other, lugs at the upper ends of said side edges extended toward the body portion of the device and outwardly 45 away from each other to form a flange to limit the downward movement of the device into the ground, the head of the scraper being doubled along a horizontal line and 50 folded over, said folded over part being provided with an extension having a slot therein to receive the projecting edges of the lower portion of the device and also having lugs at its sides folded over the back of the body 55 portion of the device to firmly unite said parts, said folded over portion of the top of the device being also provided with a flange folded over the top edge of both portions of the upper part of the device to form 60 a rounded straight edge for scraping purposes and to strengthen and reinforce the scraper at the top.

Des Moines, Iowa, Feb. 18, 1910.

JOHN C. OLIVA.
